C. H. GRANT,
TOY AIRPLANE,
APPLICATION FILED JAN. 7, 1920.

1,371,162.

Patented Mar. 8, 1921.

Charles H. Grant, INVENTOR,
BY Howard S. Smith
Attorney.

UNITED STATES PATENT OFFICE.

CHARLES H. GRANT, OF DAYTON, OHIO.

TOY AIRPLANE.

1,371,162.

Specification of Letters Patent.

Patented Mar. 8, 1921.

Application filed January 7, 1920. Serial No. 349,850.

To all whom it may concern:

Be it known that I, CHARLES H. GRANT, a citizen of the United States, residing at Dayton, in the county of Montgomery and State 5 of Ohio, have invented certain new and useful Improvements in Toy Airplanes, of which the following is a specification.

The principal object of the invention is to provide a toy airplane in which the motor is 10 longitudinally disposed between a pair of frame members. The chief advantage to be derived from this construction is, that there is no tendency for the tension of the rubber motor to bend the longitudinal members out 15 of their horizontal plane, which is the case where the rubber strands are placed above or below a single longitudinal member. Another advantage which flows from this structure is simplicity of construction, which lessens 20 the cost of manufacture.

Furthermore, the two longitudinal members provide a broad base for the main plane to rest upon, and eliminate a fitting which would be necessary to hold the plane steady, 25 as in the case of a single longitudinal member.

Another object of providing two longitudinal frame members, is to permit the fin to be firmly secured between their rear ends, 30 and their front ends to receive a simple socket fitting through which projects the propeller shaft.

Another object of the invention is to provide an under-carriage or chassis the struts 35 and axles of which, are in one piece.

Another object of the invention is to provide a chassis having an integral part which forms a spreader for the longitudinal members.

Another object of the invention is to provide between the longitudinal members and the main plane, an elevating block which gives the latter a greater angle of incidence than the tail.

Another object of the invention is to provide a flexible bearing for the propeller shaft.

And still another object of the invention is to provide a washer which turns with the propeller to prevent the wood of the latter 50 being worn as in the case of ordinary round washers.

The preferred form of embodiment of my invention is illustrated in the accompanying drawings, of which Figure 1 is a top plan view of my improved toy airplane. And Fig. 2 is a side elevational view of the latter.

Throughout the specification and drawings, similar reference characters denote corresponding parts.

Referring to the accompanying drawings, 60 the numerals 1, 1 designate two longitudinal frame members whose front ends are received by the tubular limbs of a metallic U-shaped socket 2. Secured between the rear ends of the longitudinal members 1, 1, by 65 means of nails 4, 4 and the transverse ends of a hook 5, is a vertical fin 6. The hook 5 preferably comprises a piece of wire that is looped at its upper end in a horizontal plane and then bent downwardly and rearwardly 70 to form a hook which receives rubber strands 7 that form the motor of the airplane. The free ends of the hook 5 are projected laterally from opposite directions, through the longitudinal members 1, 1, and the front portion 75 of the fin 6 between them, and are then turned inwardly against the outer faces of the longitudinal members from which they issue, firmly to secure the front portion of the fin between those members. 80

The rubber strands 7 forming the motor, pass forwardly between the longitudinal members 1, 1, to the hook end 8 of a propeller shaft 9 that loosely projects through the forward end of the socket 2 into a propeller 10. Since the rubber strands 7 pass between the longitudinal members 1, 1, they will exert no force to bend those members 85 upwardly or downwardly out of their horizontal plane. 90

It is also an advantage to have two longitudinal frame member, since they receive on their forward ends the U-shaped socket 2 which provides a flexible bearing for the propeller shaft whereby the propeller will not 95 be injured when it strikes the ground. Fitting the middle portion of the propeller 10 is a U-shaped washer 11 through which the shaft 9 loosely projects and which turns with the propeller to prevent injury to the wood 100 of which it is constructed, as is often the case when ordinary round washers are employed.

The wheels 12, 12 of the airplane turn on axles 13, 13 preferably formed of wire. These axles are the transverse integral portions of struts 14, 14, the forward free ends of which are turned around the longitudinal members 1, 1 just behind the socket 2. These struts then incline outwardly and downwardly to form the transverse axles 13, 110 13, and then project upwardly and rearwardly over the longitudinal members 1, 1.

to form between them a transverse spreader portion 15 which holds the members apart at their middle portions. Simplicity of construction and cheapness of manufacture are obtained by making the chassis in one piece, although it may be formed of several pieces without departing from the spirit of the invention.

Resting upon the tops of the longitudinal members 1, 1 is an elevating block 16, upon which is glued the front portion of the main wing 17. This block gives the main wing a greater angle of incidence than the tail piece 18 which is secured to the under side of the rear portions of the longitudinal members 1, 1 by a rubber band 19. A rubber band 20 serves to secure the main wing to the longitudinal members 1, 1. It is thus seen that the two longitudinal members 1, 1 provide at their middle portions a broad base for the main plane to rest upon, and eliminate a fitting which would be necessary to hold the plane steady, if a single longitudinal member were employed.

Having described my invention, I claim:

1. In a toy airplane, the combination with a pair of longitudinal frame members, of a rubber band motor, a vertical fin secured between the rear ends of said frame members, and a hook-shaped member whose hook end is adapted to receive the rear end of the rubber band motor and whose shank portion is adapted to be passed through said longitudinal members and fin for the purpose specified.

2. In a toy airplane, the combination with

a pair of longitudinal frame members, of a rubber band motor, an element bent to hook shape adapted to receive the rear end of said band motor, a vertical fin whose lower edge is received between the rear ends of said longitudinal members, and free ends on said hook-shaped element adapted to be passed through said longitudinal members and fin from opposite directions and bent inwardly against the outer faces of the longitudinal members from which they issue, firmly to secure the front portion of said fin between said longitudinal members.

3. In a toy airplane, the combination with a pair of longitudinal frame members, of an undercarriage secured thereto, and a transverse upper portion at the rear of said undercarriage, adapted to spread the middle portions of said longitudinal members apart.

4. In a toy airplane, the combination with a pair of longitudinal frame members, of a wire whose free ends are secured to the front ends of said frame members, said wire ends being bent downwardly and outwardly, and then laterally, to form axles, said wire ends then being inclined upwardly and rearwardly over the middle portions of said longitudinal members, with the middle portion of said wire projecting transversely between said longitudinal members to spread them apart.

In testimony whereof I have hereunto set my hand this 6th day of January, 1920.

CHARLES H. GRANT.

Witness:

HOWARD S. SMITH.
